[57] CLAIM

The ornamental design for a universal track lampholder, as shown and described.

DESCRIPTION

FIG. 1 is a front elevational view of a universal track lampholder showing our new design;
FIG. 2 is a rear elevational view of FIG. 1;
FIG. 3 is a right side elevational view of FIG. 1 (the left side elevational view being a mirror image of FIG. 3);
FIG. 4 is a top plan view of FIG. 1; and,
FIG. 5 is a bottom plan view of FIG. 1.
